CIGARETTE HOLDER

William G. Zoulfakos, Chicago, Ill.

Application September 13, 1939, Serial No. 294,715

4 Claims. (Cl. 131—173)

This invention relates to improvements in cigarette holders and one of the objects of the same is to provide an improved holder of this character in which there is employed a container for holding liquid, and through which liquid it is necessary for the smoke to pass before it reaches the mouth of the smoker, whereby the smoke will be filtered so as to remove nicotine therefrom, and at the same time the liquid will maintain the holder cool.

A further object is to provide in a holder of this character improved means whereby the smoke passage may be opened for use, and when not in use the passage may be closed so as to prevent the escape of liquid from the container.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which:

Figure 1 is a side elevation of a holder of this character constructed in accordance with the principles of this invention, with the filling water omitted.

Figures 2, 3, 4 and 5 represent an exploded view, some of the parts being in elevation and some of the parts being partly broken away and in section.

Figure 6 is a longitudinal sectional view of Figure 1 on an enlarged scale, with the water omitted.

Figure 7 is a sectional view taken on line 1—7 Figure 6.

Figure 8 is a detail perspective view of the end of the smoke passage and the means for closing the open end of the passage, the parts being in assembled relation with the passage open.

Figure 9 is a detail sectional view taken on line 9—9 Figure 6.

Throughout the specification and claims the holder will be described in connection with cigarettes but it is to be understood that it is well adapted for use with cigars.

Referring more particularly to the drawing, the holder consists essentially of a casing 10 which may be constructed of any suitable material and of any desired size and configuration, but the casing is preferably formed of transparent material.

Both ends of the casing are open and on one end is adapted to be secured a ferrule 11 which may be held in position in any suitable manner.

At the other end of the casing is arranged a mouthpiece 12 that is adapted to be frictionally held in position.

Within the casing 10 is arranged a smoke passage or conduit 13 which is preferably of a substantially U-shaped configuration, one end thereof being mounted as at 14, in a plug or member 15, the latter being reduced peripherally as at 16. At the other end of the U-shaped member or smoke passage 13 is arranged another plug 17 having peripherally reduced portions to provide ears or lugs 18, which latter preferably terminate in proximity to the extremity 19 of the plug 17. A passage 20 extends through the plug 17 and this passage is preferably located to one side of the end 21 of the smoke passage 13.

The extremity of the leg 22 of the smoke passage 13 is open, as at 23, and is adapted when the plug 17 is rotated, to be moved into and out of contact with a seat 24, which latter constitutes a closure for the open end 23 so that the smoke passage may be opened to permit smoke to be circulated from the cigarette receiving seat through an opening 26 through the seat that communicates with the leg 22 of the smoke passage, in a manner to be described.

The smoke passage 13 is of a length that when it, together with the plugs 15 and 17, are inserted into the casing 10 the plug 15 will be disposed adjacent one end of the casing while the plug 17 will be disposed adjacent the other end thereof.

The plug 15 being reduced circumferentially provides a space between its circumference and the adjacent wall of the casing 10, into which space one end of the sleeve 25 passes and is held in position by means of the ferrule 11 on the end of the casing 10 or in any other suitable manner.

The sleeve 25 forms a seat for the reception of the end of the cigarette and the plug 15 is provided with an opening 26 that has communication with the seat and also has communication with the end of one of the legs of the smoke passage 13, as shown more clearly in Figure 6.

One end of the mouthpiece 12 is reduced, as at 27, so as to be inserted into the end of the casing 10. This reduced end 27 is hollow and is provided with recesses 28 in its wall opening through the end thereof. The reduced portion 27 of the mouthpiece is adapted to be inserted into the end of the casing 10 so that the recesses 28 will receive the ears or lugs 18 on the plug 17 and if desired, a ferrule 29 may be provided on the end of the casing to hold these parts in position. A chamber 30 is formed in the mouthpiece in proximity to the adjacent extremity of

the plug 17, and the bottom of the chamber is shaped to form a valve seat 31 that encompasses the opening 32 in the mouthpiece. A valve 33 may be provided in the chamber 30 to co-operate with the valve seat 31 and this valve is provided with a stem 34 which projects into the opening 32 in the mouthpiece, the stem being of a diameter considerably less than the diameter of the passage 32 so as not to interfere with the passage 10 of smoke therethrough.

A disc 35 is provided in the chamber 30 and is held in position in any suitable manner, the function of this disc being to prevent displacement of the valve 33, there being a passage 36 through the disc 35 so as not to interfere with the circulation of the smoke through the passage in the mouthpiece 12.

When the parts are in the assembled position shown in Figures 1 and 6, the casing 18 is filled 20 with liquid which may be accomplished by removing the mouthpiece and when not in use the parts are in the position shown in Figures 1 and 3. That is, the open end 23 of the leg 22 of the smoke passage will be closed by the seat 24.

25 When the device is not in use and should the same be inverted, that is, with the cigarette receiving seat uppermost, the valve 33 will close the passage 32 through the mouthpiece 12 and the liquid will be prevented from escaping.

30 In use, after the end of the cigarette has been inserted in the receiving seat, the plug 17 is rotated by grasping either the casing 10 or the ferrule 18 and rotating the mouthpiece with respect to the casing. This will cause the end 14 of the smoke passage to turn in the plug 15 so as to open the end 23 of the leg 22, or into the position shown in either Figure 7 or 8.

With the smoke passage thus opened it will be manifest that the smoke, by drawing through 40 the passage 32 in the mouthpiece will be caused to flow from the cigarette receiving seat through the passage 26, passage 13, passage 22, through the open end 23 into the casing 18 as the passage 32 in the mouthpiece 12 has communication with the casing 10 through the opening 36, chamber 28 and passage 20.

During this operation or use, and as the holder will be held at a slightly downwardly inclined angle, the valve 33 will be unseated to open the 50 passage 32. This valve is of sufficient weight that it will not be affected by drawing through the passage 32 in the mouthpiece 12, and is also of sufficient weight that when the cigarette holder is inverted it will close the passage 32 and prevent escape of liquid.

After the use of the holder has been completed, the mouthpiece 12 is again rotated in respect to the casing 10 so as to swing the leg 22 of the smoke passage back into the position shown in 60 Figures 1 and 3 to close the open end 23 of the leg 22.

While the preferred form of the invention has been herein shown and described, it is to be understood that various changes may be made in the details of construction and in the combination and arrangement of the several parts, within the scope of the claims, without departing from the spirit of this invention.

70 What is claimed as new is:

1. A cigarette holder embodying a liquid holding casing, a cigarette seat and a mouth piece at the respective ends of the casing and each having a passage communicating with said casing, a

smoke conduit of substantial length within the casing, the ends of the conduit being disposed in proximity to each other, one end of the conduit being rotatably mounted at one end of the casing and having communication with the passage in said seat, a closure within the casing and adjacent said rotatable end of said conduit, into and out of engagement with which the other end of the conduit is movable to close the conduit and to open the same to establish communication with the interior of the casing, and means for effecting such rotation of the conduit. 10

2. A cigarette holder embodying a liquid holding casing, a cigarette seat and a mouth piece at the respective ends of the casing and each 15 having a passage communicating with said casing, a smoke conduit of substantial length within the casing, the ends of the conduit being disposed in proximity to each other, one end of the conduit being rotatably mounted at one end of the casing and having communication with the passage in said seat, a closure within the casing and adjacent said rotatable end of said conduit, into and out of engagement with which the other end of the conduit is movable to close the 20 conduit and to open the same to establish communication with the interior of the casing, means for effecting such rotation of the conduit, means mounting said mouthpiece within the casing for rotation with respect thereto, and an 25 operative connection between said mouthpiece and a portion of said conduit for effecting rotation of the conduit.

3. A cigarette holder embodying a liquid holding casing, a cigarette seat and a mouth 30 piece at the respective ends of the casing and each having a passage communicating with said casing, a substantially U-shaped smoke conduit of substantial length within the casing, the ends of the conduit being disposed in proximity to 35 each other, one end of the conduit being rotatably mounted at one end of the casing and having communication with the passage in said seat, a stationary closure within the casing and adjacent said rotatable end of said conduit, into and out of engagement with which the other end of the conduit is movable to close the conduit and to open the same to establish communication with the interior of the casing, and means for swinging said conduit about its 40 rotatably mounted end.

4. A cigarette holder embodying a liquid holding casing, a cigarette seat and a mouth piece at the respective ends of the casing and each 45 having a passage communicating with said casing, a smoke conduit of substantial length within the casing, the ends of the conduit being disposed in proximity to each other, one end of the conduit being rotatably mounted at one 50 end of the casing and having communication with the passage in said seat, a closure within the casing and adjacent said rotatable end of said conduit, into and out of engagement with which the other end of the conduit is movable to close the 55 conduit and to open the same to establish communication with the interior of the casing, said mouth piece being rotatably and detachably connected to said casing, and a separable connection between said mouth piece and said conduit for swinging the latter about its rotatably mounted end. 60
